UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION MAGNETO.

Application filed February 20, 1922. Serial No. 537,983.

My invention relates to an ignition magneto, and more particularly to an ignition magneto comprising movable inductors and a stationary coil structure.

5 Among its objects, my invention contemplates

First: The provision of an ignition magneto comprising a stationary coil structure, and primary, secondary and tertiary windings which co-operate with each other in a novel manner to produce an extremely effective high tension ignition current in the secondary.

Second: The provision in combination with the aforesaid core structure, primary, secondary and tertiary windings, of improved means co-operating with a permanently magnetic field structure for effecting and reversing the polarization of said core structure.

Third: The provision of a novel primary or low tension circuit including said primary and tertiary windings, breaker mechanism and, preferably, a condenser.

25 Fourth: The provision of an ignition magneto comprising improved means for polarizing and reversing the polarization of a stationary core structure.

Other features, objects and advantages of 30 my present invention will appear as the following detailed description progresses.

In the accompanying drawings illustrating my invention,

Figure 1 is a schematic view in perspective of an ignition magneto embodying the improvements of my invention;

Figure 2 is a vertical sectional view which may be regarded as having been taken on the line 2-2 of Figure 1; and

40 Figure 3 is a circuit diagram.

Similar characters of reference indicate corresponding parts throughout the several views.

Referring to the drawings, reference numeral 10 indicates a permanent magnet provided with opposed pole pieces 11-11. Disposed between the pole pieces is a rotor which consists of a non-magnetic body or cylinder 12 suitably journaled for rotation 50 around an axis coincident with the common center of the concave faces of pole pieces 11.

The non-magnetic body or cylinder 12 is provided at each end with diametrically opposite recesses which receive the inductors

A, AA, B and BB, the inductors A and AA being located at one end of the non-magnetic body 12, and the inductors B and BB at the other end of the body 12. Each of said inductors consists of a group of arcuate 60 soft iron laminae disposed edgewise to the axis of the rotor. Said inductors are adapted to sweep past the pole pieces 11 and the hereinafter mentioned pole structure shoes when the rotor rotates. It will be noted 65 that the inductors at each end of the rotor are staggered with respect to the inductors at the other end of the rotor.

Disposed midway between and above the pole pieces 11-11, and located at opposite 70 ends of the magneto, are the L-shaped pole structure shoes 13 and 13', the horizontal portions of said shoes being provided with concave faces concentric with the concave faces of pole pieces 11-11. Shoes 13 and 13' preferably consist of vertically disposed laminae which are held in position by having the non-magnetic material of the magneto framework cast therearound. Such non-magnetic material is indicated at X. 80

Disposed above and supported by the shoes 13 and 13', and preferably clamped thereto in any suitable manner, not shown, is a rectangular magnetic core structure 14 which consists of a plurality of vertically 85 disposed soft iron laminae suitably riveted together. Carried by the upper horizontally disposed portion of the core is a primary winding 15 having a secondary winding 16 in inductive relation thereto. Disposed upon the lower horizontal portion of the core structure is a tertiary winding 17 which preferably is formed of the same size wire as primary 15, but preferably includes approximately twice as many turns as said 90 primary.

Secondary 16 is grounded at one end and has its insulated terminal connected with the flyer of distributor mechanism 18, the said flyer being adapted to distribute high 100 tension ignition current to spark plugs 19-19 in the usual manner. While I have chosen to illustrate the distributor mechanism 18 diagrammatically, it will, of course, be understood that the flyer 18 is driven by 105 or with the magneto rotor and in timed relation to the cam of the hereinafter mentioned interrupter mechanism.

One end of the primary 15 is grounded to the magneto framework, its other end being 110

connected with the stationary or insulated contact of the interrupter mechanism illustrated at 20. The interrupter mechanism may be of conventional or any suitable design and need not be described in detail, it being understood that the four point cam forming part of the interrupter mechanism is driven by, or in timed relation to, the magneto rotor. One end of tertiary winding 17 is grounded along with the corresponding end of the primary 15, the other end of said tertiary winding being connected with the fixed or insulated contact of the interrupter mechanism. A condenser 21, which is interposed between the fixed interrupter contact and ground, serves to prevent arcing at the contacts, and furthermore co-operates with the primary and tertiary windings in the manner presently to be explained.

Referring now to Figure 1, it will be understood that when the rotor is in the position there shown, a low reluctance path between pole pieces 11-11 may be traced as follows: From the north pole of the magnet through inductor A, shoe 13, both horizontal legs of the core structure 14, shoe 13', and inductor B to the south pole of the magnet.

When the rotor is displaced approximately 90 degrees in a clockwise direction from the position illustrated in Figure 1, the direction of flux flow through core structure 14 is reversed, the flux path being traced as follows: From the north pole of the magnet through inductor BB, shoe 13', both horizontal legs of the core structure 14, shoe 13 and inductor A to the south pole of the magnet.

When the rotor is displaced approximately 180 degrees from the position illustrated in Figure 1, inductors AA and BB again reverse the direction of flux flow through the core structure, and when the rotor is displaced approximately 270 degrees from the position shown in Figure 1, inductors B and AA again reverse the flux through the core structure. The interrupter contacts open at approximately the time each inductor is leaving one of the core structure shoes, and it will be understood that each time the interrupter contacts open, the flyer of distributor 18 lies over one of the distributor segments with which it co-operates.

Now let us assume that the rotor, moving in the direction indicated by the arrow in Figure 1, is sweeping past the position shown in Figure 1. Current waves are created in primary 15 and tertiary 17, but since the interrupter contacts are closed, these waves do not at this time interfere, the primary and tertiary windings being short circuited in parallel through ground. As the inductor B leaves, or is about to leave, shoe 13', the interrupter contacts open. When this occurs,

the current from tertiary coil 17, augmented by a discharge from condenser 21, surges through primary 15 and tends to neutralize or overpower the current created in coil 15 prior to the separation of the contacts. The result is a decided and instantaneous change in the magnetic field in which the secondary 16 is disposed. Consequently, a high tension current is induced in the secondary winding and an extremely effective ignition spark is caused to pass at the spark plug with which the distributor flyer happens to be connected. The primary and tertiary windings function, in the manner described, four times during each complete revolution of the rotor.

While I prefer to provide the tertiary winding 17 with more turns than primary 15, I appreciate that a relation of the windings which provides a mere excess of capacity in winding 17 would function in much the same manner. This statement also holds true with respect to an arrangement wherein the primary and tertiary windings are identical with respect to both capacity and number of turns.

Having thus described an illustrative embodiment of my invention, I do not limit myself to the details of construction herein shown and described, but wish to cover all practical embodiments of the invention defined by the appended claims.

What I claim is new and desire to secure by Letters Patent is:

1. An ignition magneto comprising a substantially rectangular core structure, primary and secondary windings carried by one side of said core structure, said secondary winding being connected to the spark plug at one end and to the ground at the other, and a tertiary winding carried upon the opposite side of said core structure, an interrupter controlling the circuits respectively of said primary and tertiary windings, a magnet, and means co-operating therewith for polarizing the ends of said core structure and for reversing the polarity thereof.

2. An ignition magneto comprising a substantially rectangular core structure provided with parallel coil carrying portions, primary and secondary windings carried by one of said core structure portions, a tertiary winding carried by the other of said core structure portions, an interrupter controlling the circuits respectively of said primary and tertiary windings, substantially L-shaped core structure shoes associated with the ends of said core structure, a permanent magnet, pole pieces therefor, and a rotor comprising inductors adapted to co-operate with said pole pieces and said core structure shoes to polarize and reverse the polarity of said core structure.

3. An ignition magneto comprising a stationary core structure comprising parallel

side portions adapted to constitute coil cores, primary and secondary windings carried by one of said core structure side portions, a tertiary winding carried by the other of said core structure side portions, an interrupter controlling the circuits respectively of said primary and tertiary windings, shoes associated with the ends of said core structure, a permanent magnet, pole pieces therefor, and a rotor operating be- tween said pole pieces and comprising four segmental inductors, there being two of said inductors at each end of the rotor, the inductors at each end of the rotor being adapted to co-operate with one of said core structure shoes. 15

In witness whereof, I hereunto subscribe my name this 27th day of January, 1922.

WILLIAM W. HAWKINS.
